UNITED STATES PATENT OFFICE.

JOHN E. MANN, OF SNOHOMISH, WASHINGTON.

INDICATING DEVICE.

Application filed December 27, 1926. Serial No. 157,183.

This invention relates to an advertising novelty and information device, and more particularly to a device for indicating distances between certain places and for indicating other items such as prices of oil, gasoline, etc.; the principal object of the invention being to provide a device of the above character that may be used advantageously for the purposes above stated at 10 gasoline stations, tourists' camps, and similar places.

More specifically stated, it is the object of the invention to provide a device of the above character embodying a supporting 15 frame structure wherein discs are rotatably mounted and which bear certain information which is rendered intelligible when brought by rotative movement of the discs into registering alinement with information that is 20 contained on the frame structure.

In accompanying these and other objects of the invention, I have provided the improved details of construction the preferred forms of which are illustrated in the accompanying drawings, wherein—

Figure 1 is a face view of an advertising device and indicator embodied by the present invention; certain parts of the frame structure being broken away for the purpose 30 of better illustration.

Figure 2 is a vertical section taken on the line 2—2 in Figure 1.

Figure 3 is a central, horizontal section on the line 3—3 in Figure 1.

Referring more in detail to the drawings—

The frame, or supporting structure, of the device comprises front and rear, spaced standards 1 and 2 which at their lower ends 40 are adapted to be fixed to any supporting means, such as a post or the like as indicated at 3, and at their upper ends they are bent toward each other and are secured together by any suitable means, such as the rivets 4.

Disposed between the standards 1 and 2, is a circular disc 5 that is revolvably mounted on a bolt 6 that is extended between the standards and which has a wing nut 7 50 threaded thereon that may be tightened for the purpose of drawing the frame parts together and against the disc sufficiently to hold the latter, by frictional contact, against freely rotating, and yieldable at different 55 positions of adjustment.

Disposed concentrically of the disc 5

against its opposite side, are discs 8 and 9. These are of lesser diameter than the disc 5 and leave the peripheral portion of the latter exposed for the display of advertising 60 matter or information that may be printed or otherwise placed thereon as is shown at 10.

Printed in radial alinement about the peripheries of the exposed surfaces of the discs 8 and 9, are the names of cities, towns or localities and these names are so located that they may be individually brought, by rotation of the discs, into registering alinement beneath the outer end portions of slots 12 that are formed horizontally in circularly enlarged portions 13—13' of the standards 1 and 2; these circular enlargements being concentric with respect to the bolt 6, but are of lesser diameter than the discs 8 and 9 so 75 as to leave the peripheral portions of the latter, whereon the names are printed, exposed. Printed or marked on the enlargements 13—13' at spaced intervals along the slot 12, are the names of localities that may 80 or may not be on the discs 8 and 9. The present drawing shows the names, "Seattle," "Tacoma" and "Everett" adjacent this slot while on the discs 8 and 9, among other names, is the name "Portland." Printed on 85 the discs 8 and 9 in radial alinement with the names of the localities about their peripheries and also arranged in circular alinement about the center of the disc at such distances from the center that they will be 90 exposed through the slots 12 directly in alinement beneath the names of the localities that are printed on the frame parts, are certain numerals which designate the distance in miles between the locality with 95 which they are alined when exposed within the slots 12, and the localities marked on the peripheries of the discs in radial alinement therewith. For example, alined with the name "Portland" on the disc 8 are the numerals "210, 168 and 240" which, by that rotative movement of the disc which will bring the name "Portland" into registering alinement beneath the slot 12, will respectively be exposed in the slot directly beneath the 100 names "Seattle," "Tacoma" and "Everett," thereby indicating the distance in miles between these localities and the city of Portland.

The circular enlargements 13—13' of the 110 frame parts are only of such diameter as to cover the areas of the discs lying within the

circle of names about their peripheries. This leaves the names exposed, and since they are preferably alphabetically arranged, any desired name may be easily located.

5 There are radial extensions 16 at opposite sides of the parts 13-13' and slots 12 are extended into these extensions so that the name of a locality selected on the discs 8 and 9 may be exposed beneath the slot when 10 a reading is to be made.

I have also provided segmental pieces of discs 18 and 19 which are pivotally mounted on the bolt 6 and which have circular rows of numerals thereon adapted to be moved 15 into alinement with the names of certain products or articles for sale, which are printed adjacent horizontal slots 25 formed in the parts 13-13' diametrically alined with the slots 12, to indicate the prices of 20 such articles or products. The present drawing shows the words "Gas" and "Oil" printed on the frame adjacent the slot 25, and the discs 18 and 19 bear rows of numerals which may be brought into alinement 25 with these words to indicate the price at any certain time.

As a means of stiffening the discs 8 and 9 and also to provide means for facilitating their rotative movement, I have provided 30 them with out-turned peripheral flanges 26

which form finger grips for adjusting them to different positions.

Devices of this character may be made in various sizes and may be mounted and used in various ways and they afford an easy and satisfactory way of displaying advertising matter and for dispensing certain information that is frequently asked for at tourists' camps, gasoline stations and similar places.

Having thus described my invention, what 40 I claim as new therein and desire to secure by Letters-Patent, is:

The combination with a supporting post, of an indicating device comprising spaced standards fixed at their lower ends to opposite sides of the post and joined together at their upper ends, a pivot bolt extended between the standards and disks rotatable on the pin between the standards; said standards having circularly enlarged portions concentric with respect to the pin which are provided with radially directed slots through which matter on the disks may be observed and a clamping nut on the pin whereby the standards may be drawn together to hold 55 the disks at adjusted positions.

Signed at Everett, Washington this 1st day of December, 1926.

JOHN E. MANN.
